UNITED STATES PATENT OFFICE.

JAMES G. HALLAS, OF WATERBURY, CONNECTICUT, ASSIGNOR TO S. ELWOOD
MAY, OF NEW YORK, N. Y.

LAMP.

SPECIFICATION forming part of Letters Patent No. 331,009, dated April 10, 1888.

Application filed April 4, 1887. Serial No. 233,611. (No model.)

To all whom it may concern:

Be it known that I, JAMES G. HALLAS, of Waterbury, in the county of New Haven and State of Connecticut, have invented a certain new and useful Improvement in Lamps, of which the following is a specification.

The object of my improvement is to prevent oil which may overflow the tip of the wick-tube from flowing down upon the reservoir of the lamp, or from the lamp to any article upon which the lamp may be placed, and also to afford a convenient support for the chimney-gallery and air-distributors.

I will describe in detail a lamp embodying my improvement, and then point out the novel features in a claim.

In the accompanying drawings, Figure 1 is a side view of a lamp embodying the improvement, certain parts being shown in vertical section. Fig. 2 is a vertical section of the upper part of the wick-tube and the collars which are combined therewith. Fig. 3 is a horizontal section of the wick-tubes and appurtenances thereof. This section is not taken directly in one plane, but at the exterior of the burner is taken at the plane of the dotted line $\alpha\alpha$, Fig. 1, just above the outer collar, which is combined with the wick-tube for catching overflowing oil, and at the central portion is taken above the inner collar, which is combined with the wick-tube for the same purpose.

Similar letters of reference designate corresponding parts in all the figures.

I will only describe those features of the lamp which embody my improvement.

A' A^2 designate, respectively, the outer and the inner walls of an annular wick-tube. They are arranged one outside the other, and the outer one is sufficiently larger than the inner to afford a space between it and the inner for the accommodation of a circular wick, B.

C' designates a collar made in the shape of a gutter and extending around the exterior surface of the outer wall, A' , of the wick-tube.

C^2 designates a collar extending around the inner surface of the inner wall of the wick-tube and made gutter-shaped.

The two walls A' A^2 of the wick-tube and the collars C' C^2 will preferably be made of sheet metal. The collars C' C^2 are bent or made to

extend inwardly at the lower edges, so as to fit snugly around the surfaces of the walls of the wick-tube with which they are combined. At the extreme lower edges they are secured by solder or analogous means to the surfaces around which they extend. Each of these collars is continuous or endless. I mean by this that each extends entirely around the wall of the wick-tube with which it is combined. At the upper edges the collars are located at a short distance from the surfaces around which they extend, so that spaces or gutters will be formed by them in conjunction with the walls of the wick-tube.

J designates an air-distributer, which is supported at its lower end upon an annular shoulder, d , formed on the collar C' . About midway in the height of this distributor is an internal circumferential groove, e . This groove forms an annular projection on the outer surface of said distributor. A diaphragm, f , having a flange at its outer edge adapted to engage the said annular groove, extends between said air-distributer and the outer wall of the wick-tube. The portion of said diaphragm adjacent to the wick-tube is provided with an upwardly-turned flange fitting loosely about the wick-tube. The upper edge of this flange is turned outwardly or away from the wick-tube, in order that oil descending along the exterior of the outer wall of the wick-tube may pass between said upwardly-turned flange and the wick-tube. Oil, after passing between said upwardly-turned flange and the wick-tube, will descend into the gutter formed by the collar C' .

The walls of the wick-tube are provided with perforations a' a^2 at the portions around which the collars C' C^2 extend.

Any oil overflowing the wick-tube at the tip and running down the exterior surface of the outer wall, A' , or the interior surface of the inner wall, A^2 , will be caught by the collar C' or C^2 , and will flow thence through the perforations a' or a^2 back through the wick-tube and into the wick B.

My improvement obviates the flowing of oil over lamps, or the running of oil from lamps onto tables or other articles upon which the lamps may be placed, and withal at a very slight expense.

It will be seen that the chimney-gallery, the deflectors, and the air-distributers are all supported upon the annular shoulder *d* on the collar *C'*. By this means contact with the wick-tube is avoided and the escape of oil through the perforations in the lower part of the air-distributer is guarded against. At the same time the parts are braced or stayed against lateral or rocking movement.

10 What I claim as my invention, and desire to secure by Letters Patent, is—

The combination, with a lamp having an annular wick-tube, of a collar surrounding the outer wall of the wick-tube near its lower end 15 so as to form an open-topped gutter, and pro-

vided with an external annular flange, of an air-distributer supported upon said flange so as to be maintained at a distance from the wick-tube, the outer wall of the wick-tube being provided opposite said collar with perforations, 20 and a diaphragm supported by said distributer and extending between the same and the wick-tube, and provided at its upper edge with a portion turned outwardly or away from the wick-tube, substantially as specified.

JAMES G. HALLAS.
